UNITED STATES PATENT OFFICE.

EDWIN N. TAYLOR, OF CEDAR RAPIDS, IOWA.

LADDER-SUPPORT.

1,393,922.

Specification of Letters Patent. Patented Oct. 18, 1921.

Application filed January 18, 1920. Serial No. 351,962.

To all whom it may concern:

Be it known that I, EDWIN N. TAYLOR, a citizen of the United States, residing at Cedar Rapids, in the county of Linn and State of Iowa, have invented certain new and useful Improvements in Ladder-Supports; and I do hereby declare the following to be a full, clear, and exact description of the invention, such as will enable others skilled in the art to which it appertains to make and use the same.

This invention relates to attachments for ladders, in the nature of a projecting bracket or foot, and the object of this invention is to produce a simple device adapted to hold the ladder outwardly at the upper end; to serve as a support for a foot-board, or to act as legs to support the lower end of the ladder, either in an upright or a practically horizontal position on an inclined surface, as a roof, or the like.

The invention is fully disclosed in the description and claims following, reference being had to the accompanying drawing, in which:—

Figure 1 is a view in perspective of my improved ladder-support as applied to a ladder. Fig. 2 is a perspective view of the same inverted, one of the leg-extensions being removed.

In the drawing, the numeral 5 denotes a ladder, provided with the usual round rungs 6. The principal part of the ladder-support is a stirrup-like strut 7, formed of steel bar material, the ends of the legs being preferably, but not necessarily pointed, as shown. To the cross-member 8 is secured, as by rivets 9, a stirrup 10, which gives space between its free side and the opposite part of the ladder-support, to receive one of the ladder rungs. A simple latch 11, which may be merely a bent wire, with its shank pivoted in a fold of the stirrup 10, serves to hold the support from displacement.

For some purposes this structure is sufficient. It is especially convenient and useful in such operations as house-painting, when the operator uses only a single ladder. In this case the upper end of the ladder rests against the side of the building, and it is of course impossible to paint the surface against which the ladder rests, and this necessitates going down and shifting the position of the ladder. But by means

of this support the upper end of the ladder may be removed from the surface to be painted, the operator with one hand pushing against the building, and with the other grasping the stirrup part of the support, pulling outwardly on the ladder, and adjusting the legs of the support to the desired position. The stirrup part thus serves as a holder for the support, and as a convenient means for turning it on the ladder rung. After painting close to the legs, the operator has only to turn the legs up or down, as the case may be, to bear on the painted portion, making it thus possible to paint the entire surface without shifting the foot of the ladder.

Provision is made, however, for using the support for other purposes. In Fig. 1 the ladder is shown projecting above the eaves of a house outside the rain trough. It is of course detrimental to lean the ladder against such a trough, but to give access to the roof the upper end of the ladder should extend above the cornice. The holder in this case is used to hold the upper end of the ladder away from the eaves, which it does in the manner already described in connection with painting. The holder is best provided, however, with extensions 12, slidable on its legs, so as to allow for adjustment in the length of the legs as circumstances may require. By means of holes 13 in the connected parts, they may be fastened at any desired place by an engaging part, which is here shown as a hook 14 at the end of a chain 15. One of these is attached to each leg of the support, and by diverging them as shown the holder is securely anchored in any desired position, by passing the chain around adjoining rungs and hooking the free ends of the chain to the links of the chain, as indicated.

In Fig. 2, which shows the device inverted, the suspending chain is shown attached near the outer end of one of the legs. This permits a plank to be slipped between the chain and ladder, and thus, by the use of a pair of ladders, a staging may be easily and conveniently erected for painting or other work at the side of a building.

It will be evident that by securing the support to the bottom rung of a ladder, and nearly vertical, the pointed legs will serve in whole or in part to support the ladder

when erected on an inclined surface, as on the roof of a porch or lean-to, and thus prevent any possible slipping of the foot of the ladder. When set at substantially the angle shown in Fig. 1, but attached to a rung near the end of the ladder, the latter may be laid down on a roof of moderate pitch, and the legs on the lower part of the roof will support the ladder approximately level, to support a footboard, or the like, in that position.

In Fig. 1 is shown an auxiliary brace 16, which may be used with or without the chains. It is intended to merely carry the weight of the support, and prevents it from dropping when a supporting chain is loosened, or entirely detached. This brace is provided with a simple hook 17, tending to pinch the side of the ladder, and thus hold the support in position. It serves to hold the support in the position shown in Fig. 1, when no board or other extra weight is applied, and also to hold the support parallel with the sides of the ladder so that in an extension ladder the parts may slide freely without the support interfering in any way.

Having thus described my invention, I claim:

1. A ladder support, comprising a stirrup-shaped bracket, the legs thereof being adapted to rest against a building and hold the ladder out therefrom, and a transversely disposed, elongated stirrup attached to the cross-bar of the bracket, and adapted to hold the bracket on a rung of the ladder, and to be grasped by a hand and used as a handle in turning the bracket on the rung.

2. A ladder support, comprising a stirrup-shaped bracket, a transversely disposed, elongated stirrup attached to the cross-bar of the bracket to engage a rung of the ladder, and means for locking the rung-engaging stirrup in position, said rung engaging stirrup being adapted to be grasped as a handle by the hand in turning the bracket on said rung.

In testimony whereof I affix my signature in presence of two witnesses.

EDWIN N. TAYLOR.
